VENDING MACHINE

Emery Mihalek, Chicago, Ill., assignor to Hershey Mfg. Co., Chicago, Ill., a corporation of Illinois

Application February 21, 1956, Serial No. 566,874

5 Claims. (Cl. 221—11)

This invention relates to machines for vending various articles, particularly paper milk cartons or the like.

One object of the present invention is to provide a new and improved vending machine that will hold a large number of milk cartons or other articles yet will vend the cartons positively and expeditiously.

A further object is to provide a vending machine in which successive rows of articles are carried to a delivery position in channel-shaped guide elements carried by an endless conveyor, and in which the rows of articles are pushed along the guide elements at the delivery position so that each article in turn will be pushed off the conveyor.

It is another object to provide a new and improved vending machine having a cabinet with a front wall formed with an opening through which vended articles are removed, together with a door arranged to swing closed by its own weight so as to close the opening.

A further object is to provide a vending machine which is effective and foolproof in operation yet is simple in construction and low in cost.

Further objects and advantages of the invention will appear from the following description, taken with the accompanying drawings, in which:

Fig. 1 is a perspective view of a vending machine constituting an illustrative embodiment of the present invention.

Fig. 2 is a vertical sectional view taken generally along a line 2—2 in Fig. 1.

Fig. 3 is a horizontal sectional view taken generally along a line 3—3 in Fig. 1.

Fig. 4 is a fragmentary enlarged sectional view taken generally along a line 4—4 in Fig. 2.

Fig. 5 is a fragmentary perspective view showing the machine of Fig. 1 with its outer door standing open to reveal an inner door.

Fig. 6 is a perspective view showing the machine with both the outer and inner doors standing open.

Fig. 7 is a fragmentary front elevational view showing one of the two vending units embodied in the machine.

Fig. 8 is an elevational sectional view taken generally along a line 8—8 in Fig. 7.

Fig. 9 is an elevational sectional view taken generally along a line 9—9 in Fig. 7.

Fig. 10 is a plan view of the vending unit shown in Fig. 7.

Fig. 11 is an enlarged fragmentary elevational sectional view taken generally along a line 11—11 in Fig. 10.

Fig. 12 is a schematic electrical circuit diagram of the vending machine.

As already indicated, Fig. 1 is a general perspective view of a vending machine 20 adapted to dispense various articles, particularly waxed paper cartons filled with milk. The machine will vend either flat-topped cartons 22 or gable-topped cartons 24 of square cross-section. Both types of cartons may be intermixed in the machine. Any of the usual sizes of cartons, from one-half pints to quarts, may be dispensed by the illustrated machine. Of

2

course, it would be a simple matter to build a machine proportioned so as to handle one-half gallon cartons.

The vending machine 20 is really two machines in one, inasmuch as the machine embodies twin upper and lower vending units 26, as will be seen from Fig. 6. The vending units 26 may be substantially identical in construction.

It will be seen from Fig. 1 that the vending machine 20 comprises a generally rectangular cabinet 28. An outer door 30 is hinged on the cabinet 28 so that the cabinet may be opened by a serviceman for the purpose of filling the vending units 26 with milk cartons. Two coin slots 32 are provided on the front door 30 to actuate the individual vending units 26. Moreover, each

vending unit 26 has a small carton door 34 disposed in an opening 36 through which the vended cartons may be removed by the purchaser. When a suitable coin is deposited in one of the coin slots 32, the corresponding vending unit 26 will deliver a milk carton to a housing

38 disposed immediately behind the corresponding opening 36 in the front of the cabinet 28. The door 34 is preferably made of transparent material so that the carton will be visible. The purchaser will open the door 34 and remove the carton through the opening 36.

Each of the doors 34 is arranged so that it will close automatically by virtue of its own weight. Thus, each door 34 is mounted on hinge pivots 40 extending along an axis which is tilted slightly in a rearward direction, from bottom to top, rather than being strictly vertical.

When the door 34 is opened, gravity will tend to swing the door closed. To prevent the door from standing in its fully open, dead center position, each door is arranged to engage a spring-biased pin 42, just before the door reaches its fully open position. Each of the pins 42 is slidably mounted on the cabinet 28 and is biased outwardly by a spring 44. Thus, the closing movement of the door 34 is started by the pin 42 and is completed by the action of gravity on the door.

From Fig. 5, it will be seen that the carton-receiving housings 38 are mounted on an inner door 46, shown standing open in Fig. 6. The inner door 46 also supports coin-selecting mechanisms 48 for the two vending units 26. In this instance, the machine is equipped with change-making mechanisms 50 adapted to return one or more pennies or other small coins to the purchaser through coin return openings 52 in the outer door 30. The detailed constructions of the coin-selecting mechanisms 48 and the change-making mechanisms 50 are not material to the present invention.

The vending units 26 may be arranged in various ways, but in this instance, each of them is provided with a horizontal frame 54. Since the two vending units 26 are substantially identical, it will be sufficient to describe the upper unit. In order that the vending unit 26 may readily be removed from the machine for servicing, the frame 54 is movably supported in the cabinet 28 on channel-shaped horizontal rails 56 and 58 secured to the inside of the cabinet on opposite sides thereof. Bars 60 and 62 are mounted on the left- and right-hand ends of the horizontal frame 54 and are adapted to be slidably received in the channels of the rails 56 and 58. In order to prevent accidental forward movement of the vending unit 26, a removable pin 64 may be inserted through aligned apertures in the rail 58 and the bar 62.

A drip pan 66 is provided immediately below the vending unit 26 and is removably received in additional channel-shaped rails 68 and 70 which are secured to the inside of the cabinet immediately below the rails 56 and 58.

It will be understood that the entire vending unit 26 may readily be slid forwardly on the rails 56 and 58. The vending unit may be slid part way out of the cabinet for filling and minor servicing. Moreover, the unit 26

may be removed entirely and replaced with a spare unit.

The milk cartons 22 or other articles to be vented are supported on an endless flexible conveyor 72, which might assume various forms, but in this instance comprises a pair of endless chains 74 strung around sprockets 76 and 78. It will be seen that the sprockets 76 and 78 are mounted on shafts 80 and 82 which are parallel and at the same horizontal level, but are spaced apart horizontally from left to right. An electric gear motor 84 having a low output speed is provided to drive the shaft 80 so as to advance the chains 74. Each chain 74 has an upper horizontal flight 86 which advances from left to right, and a lower horizontal flight 88 which returns from right to left.

In this instance, the milk cartons 22 are actually supported in guide channels 90 provided by channel-shaped members 92 carried by the chains 74. It will be seen that each of the channel members 92 has a bottom wall 94 and a pair of side flanges 96. Longitudinal ridges 98 are provided in the bottom wall 94 so that the cartons 22 will be spaced above the bottom wall 94. In this way, any milk escaping from a leaky carton can flow along the bottom wall 94 and drain off the end of the channel member 92 into the drip pan 66.

The channel members 92 are spaced closely together from left to right and are arranged to extend from front to rear between the conveyor chains 74. Each of the channel members 92 is pivotally mounted on the conveyor chains 74 by means of a pair of angle brackets 100. It will be seen that one flange of each bracket 100 is bolted or otherwise secured to the bottom wall 94, while the other flange is pivotally connected to one of the chains 74. The channel members 92 are spaced a short distance away from the chains 74. By virtue of this mounting arrangement, the channel members 92 will pass freely around the sprockets 76 and 78 and will hang suspended from the lower flights 88 of the chains 74. Along the upper flights 86, the channel members 92 are supported by horizontal guide rails 102 (Fig. 9). In this way, the weight of the milk cartons 22 is carried by the rails 102, rather than by the chains 74. The channel members 92 slide along the underlying rails 102 in passing along the upper flights 86 of the chains 74.

Each of the channel members 92 is adapted to receive a number of the milk cartons 22 arranged in a row extending from front to rear. A rail 104 is mounted on the inside of the rear cabinet wall to prevent the cartons 22 from being moved rearwardly in the channel members 92 beyond the desired rear limit. Likewise, a rail or bar 106 is mounted on the inner door 46 to retain the cartons 22 on the channel members 92 against accidental forward movement.

During the operation of the vending unit 26, the conveyor motor 84 is effective to bring each channel member 92 and the accompanying row of milk cartons 22 to a delivery position 108 at the right-hand end of the upper chain flights 86. At this position, the row of cartons is moved forwardly so that each carton in turn will be pushed off the front end of the channel member 92. After all of the cartons in the row have been vended, the conveyor motor 84 will again be energized to advance the next row of cartons to the delivery position 108. As the cartons arrive at the delivery position 108, they engage a horizontal bail or rod 110 extending between the lower ends of supporting arms 112. It will be seen from Fig. 7 that the arms 112 are swingably suspended from pivots 114 and are biased to the left by a spring 116. When the cartons 22 move to the delivery position 108, they swing the bail 110 and the arms 112 to the right. This has the effect of stopping the conveyor motor 84. The motor 84 is actually controlled by a switch 118 which is operated by a cam 120 when the bail 110 is swung to the right. The cam 120 takes the form of a flange on the front supporting arm 112. It will be seen from Fig. 9 that

5 a second switch 122 is also adapted to be operated by the cam 120. The second switch 122 functions as a safety switch for the vending mechanism, as will be explained shortly.

When all of the cartons 22 at the delivery position 108 have been vended, the spring 116 swings the bail 110 and the supporting arms 112 to the left until the supporting arms 112 encounter stop pins 124. This movement of the bail 110 has the effect of starting the conveyor motor 84.

The cartons 22 at the delivery position 108 are moved off the conveyor 72 by means of a vending mechanism 125 of the general type described and claimed in my copending application, Serial No. 487,307, filed February 10, 1955, and entitled "Machine for Vending Cartons or Other Articles." Thus, the vending mechanism 125 comprises a pusher paddle 126 adapted to engage the rear side of the rearmost carton in the row. The paddle 126 is slidably mounted on a pair of rods 128 for reciprocating movement forwardly and rearwardly over the channel member 92 at the delivery position 108. It will be seen that the paddle 126 is of sufficient vertical extent to push any of the usual sizes of cartons, from one-half pints to quarts.

25 For the purpose of advancing the pusher paddle 126, the vending mechanism 125 is provided with an endless drive element in the form of a chain 130 strung around front and rear sprockets 132 and 134 which are at the same horizontal level. A slow-speed electric gear motor 136 is utilized to drive the rear sprocket 134. The chain 130 is adapted to advance the pusher paddle 126 by means of a pair of outwardly projecting fingers or arms 138 mounted on the chain at equally spaced points. Each of the fingers 138, after moving around the rear sprocket 134, is adapted to engage the rear side of a flange 140 on the pusher paddle 126. Further advancing movement of the chain 130 will carry the pusher paddle 126 forwardly until the finger 138 moves downwardly around the front sprocket 132, whereupon the finger will become disengaged from the flange 140. Immediate retraction of the pusher paddle 126 is then brought about by a spring 142 which continuously biases the paddle rearwardly. From Figs. 8 and 9 it will be seen that the spring 142 is in the form of an elongated coil spring having its front end connected to a fixed anchor 144 adjacent the front of the vending unit 26. The spring 142 extends rearwardly and is threaded around a pulley 146 so that the opposite end of the spring can be brought forwardly and connected to the pusher paddle 126.

152. It is actually the release of the switch 158 which stops the vending motor 136, as will be described in greater detail shortly. When the switch 158 is operated by the return of the trip lever 152, the vending unit is conditioned for further operation by the depositing of another coin.

The vending mechanism 125 is arranged so that the vending motor 136 will continue to operate after the last carton in the row at the delivery position 108 has dropped into the delivery chute 148. In this way, the chain 130 continues to advance until the finger 138 is disengaged from the pusher paddle 126. Such disengagement is necessary to permit retraction of the pusher paddle 126 by the spring 142. In this instance, such continued operation of the vending motor 136 is brought about by an override switch 160 adapted to be operated by the pusher paddle 126 as it approaches the position at which the last carton drops into the delivery chute 148. More specifically, the switch 160 is operated by a cam in the form of a flange 162 on the pusher paddle 126. Operation of the switch 160 overrides the action of the delivery switch 158 and results in continued operation of the vending motor 136. Once the driving finger 138 has become disengaged from the pusher paddle 126, the spring 142 completely retracts the pusher paddle so that the override switch 160 is no longer operated. This stops the vending motor 136, in a manner to be described in detail shortly.

When the pusher paddle 126 has been fully retracted, it operates a safety switch 164 (Fig. 10), which conditions the vending unit 26 for operation of the conveyor 72. Until the switch 164 is operated, the conveyor 72 is prevented from operating, in a manner that will be explained in detail shortly. For the conveyor to operate, it is also necessary that the bail 110 swing to the left, as already indicated.

Consideration will now be given to the schematic electrical diagram of the vending unit 26, as shown in Fig. 12. It will be seen that the vending unit receives electrical power from a line plug 166 adapted to be connected to an ordinary alternating current powerline, which may be at 110 volts. Lead wires 168 and 170 are connected to the plug 166 to receive the alternating voltage. A third lead 172 is connected between the frame of the vending unit and the plug to ground the frame in the usual manner.

In order to refrigerate and ventilate the interior of the cabinet 28, the machine 20 is provided with a refrigerator motor 174 and a blower motor 176, which drive a suitable refrigeration compressor and a blower (not shown). A rheostat 178 is connected in series with the refrigerator motor 174 to regulate the temperature in the cabinet 28. The motors 174 and 176 receive their power from the leads 168 and 170 through a switch 180 which is closed when the outer door 30 is closed but is open when the door is open. In this way, the motors 174 and 176 are automatically stopped when the outer door 30 is opened.

The machine is arranged so that the vending units 26 will not operate unless the interior of the cabinet 28 is cold. This arrangement makes it impossible for the machine to vend warm milk. For this purpose, the machine 20 is provided with a temperature control relay 182 having normally open contacts 182a which are connected between the lead 168 and lead 184. The leads 170 and 184 are connected through a double pole on-off switch 186 and a pair of fuses 188 to a pair of power-line leads 190 and 192 on each of the vending units 26.

One side of the temperature control relay 182 is connected to the lead 192, while the other side of the relay is connected through a thermostatic switch 194 to the lead 168. Thus, the relay 182 is energized whenever the main switch 186 and the thermostatic switch 194 are closed. The thermostatic switch 194 is arranged to close whenever the temperature in the cabinet 28 is below a

predetermined value, such as 50° F., for example. When the relay 182 is energized, the contacts 182a are closed and the vending units 26 are supplied with power. However, the supply of power is cut off whenever the temperature in the cabinet rises above the desired level.

It will be understood that each of the vending units 26 has a main switch 186 and fuses 188. Moreover, the other electrical components, shown in the circuit diagram and now to be described, are found on each of the vending units 26.

When a coin is deposited in the coin slot 32 for the vending unit 26, the coin operates a switch 196 having a contact 198 which is movable between fixed contacts 200 and 202. The coin shifts the movable contact 198 from the contact 200 to the contact 202. After the coin has passed the switch 196, the movable contact 198 returns to the contact 200. It will be understood that the coin switch 196 is embodied in the coin-selecting mechanism 48 for the vending unit 26.

It will be seen that the movable contact 198 is connected to the powerline lead 190. A first vending relay 204 is connected between the contact 202 and the power lead 192 by means of leads 206 and 208. Thus, movement of the contact 198 against the contact 202 energizes the relay 204. It will be seen that the relay 204 is equipped with normally open contacts 204a and 204b and normally closed contacts 204c. The normally open contacts 204a are utilized to control a circuit extending between the switch contact 200 and the power lead 192, and including a lead 210, the contacts 204a, a lead 212, a second vending relay 214, and a lead 216. Thus, closure of the contacts 204a conditions the second vending relay 214 for energization when the movable switch contact 198 returns to the contact 200.

The first vending relay 204 is locked in by closure of its own contacts 204b, which thus serve as holding contacts. A holding circuit may be traced between the power lead 190 and the relay lead 206 through a lead 218, the override switch 160, a lead 220, the delivery switch 158, a lead 222, the contacts 204b, and a lead 224. Thus, both the override switch 160 and the delivery switch 158 must be in the proper positions before the relay 204 will hold in. In this case, it should be noted that all of the relays and switches are shown in the positions they occupy when the vending unit is empty and stationary. It will be seen that the delivery switch 158 is closed by virtue of being operated by the trip lever 152 in its normal position.

The override switch 160 comprises a contact 226 which is movable between contacts 228 and 230. The lead 218 is actually connected to the movable contact 226, while the lead 220 is connected to the fixed contact 228. When the override switch 160 is not being operated, the movable contact 226 engages the contact 228 and completes the holding circuit for the relay 204. Thus, the relay 204 is locked in until the trip lever 152 is operated by the vended carton. Such operation of the trip lever 152 opens the delivery switch 158 and de-energizes the relay 204. Further discussion of the normally closed contacts 204c will be reserved for a later point in the description.

In this instance, the second vending relay 214 is provided with normally open contacts 214a and normally closed contacts 214b and 214c. It will be noted that the relay 214 is energized when the coin switch 198 returns to its normal position but is not energized if the coin hangs up on the coin switch. This arrangement prevents the vending unit from discharging its entire contents in the event that a coin should hang up. Instead, the unit will not operate at all if the coin hangs up.

Closure of the normally open contact 214a is effective to start the vending motor 136, provided the vending motor safety switch 122 is operated. An energizing circuit for the vending motor 136 may be traced from the lead 222 to the power lead 192. Such circuit in-

cludes a lead 231, the contacts 214a, a lead 232, the safety switch 122, a lead 234, a normally closed thermostatic switch 236, the vending motor 136, and a lead 238. The thermostatic switch 236 is of the usual type which remains closed unless the vending motor is overloaded, whereupon the switch will open to protect the motor from being damaged. The safety switch 122 is shown in its open position since this is the position it occupies when the vending unit is empty. However, with one or more cartons at the delivery position, the bail 110 is displaced to the right and the switch 122 is closed to permit operation of the vending motor 136. Thus, closure of the relay contacts 214a starts the vending motor 136. The motor 136 continues to operate until the delivery switch 158 opens due to the actuation of the trip lever 152 by the vended carton. As already indicated, the opening of the delivery switch 158 de-energizes the first vending relay 204. De-energization of the first relay 204 opens the contacts 204a and thereby de-energizes the second vending relay 214. This sequence of operations conditions the vending unit for subsequent actuation by the depositing of another coin.

It has already been noted that the override switch 160 has the effect of continuing the operation of the vending motor 136 after the last carton in the row at the delivery position has opened the delivery switch 158. The override switch 160 is operated by the pusher paddle 126 as it approaches the position at which the last carton is vended. Such operation shifts the movable contact 226 into engagement with the contact 230. It will be seen that a lead 240 is connected between contact 230 and the lead 232 and then through the safety switch 122 to the motor 136. Thus, the override switch 160, when operated, bypasses the delivery switch 158 and the relay contacts 214a so that the vending motor 136 continues to operate. Such operation continues until the override switch is returned to its normal position by the retraction of the pusher paddle 126.

Retraction of the pusher paddle operates the conveyor safety switch 164, which is provided with a contact 242 movable between contacts 244 and 246. Operation of the safety switch 164 shifts the movable contact 242 from the contact 244 to the contact 246 and is effective to energize a conveyor motor relay 248. An energizing circuit for the relay 248 may be traced from the power lead 190 through a lead 250, the contacts 242 and 246, a lead 252, normally open contacts 254a of a relay 254, a lead 256, the conveyor switch 118, a lead 258, the relay 248, and a lead 260 to the power lead 192. It will be apparent that the relay 248 is energized when the switches 118 and 164 and the contacts 254a are closed. During normal operation of the vending unit, the contacts 254a are always closed, as will be explained shortly. Thus, closure of the switches 118 and 164 is sufficient to energize the relay 248. The conveyor switch 118 is closed when the bail 110 swings outwardly after the last carton at the delivery position has been vended. The safety switch 164 is closed by the return of the pusher paddle 126.

It will be seen that the conveyor relay 248 is provided with normally open contacts 248a. An energizing circuit for the conveyor motor 84 may be traced from the power lead 190 through a lead 262, the contacts 248a, a lead 264, a normally closed stop switch 266, a lead 268, normally open contacts 254b of the relay 254, a lead 270, a normally closed thermostatic switch 272 similar to the switch 236, the conveyor motor 84, and a lead 274 to the power lead 192. During normal operation of the vending unit 26, the relay contacts 254b and the stop switch 266 are closed. Thus, closure of the contacts 248a is sufficient to energize the conveyor motor 84. The stop switch 266 may be of the pushbutton type and is provided so that the serviceman may stop the conveyor at any time when he is filling or servicing the machine.

10 The conveyor motor 84 stops when the new row of cartons reaches the delivery position 108 and pushes the bail 110 to the right. This opens the conveyor switch 118, which de-energizes the relay 248, opens the contacts 248a, and thereby de-energizes the motor 84.

15 The relay 254 may be of the mechanical lock-in or interlocked type, provided with separate actuation and release windings 254c and 254d. Momentary energization of the winding 254c actuates all of the contacts of the relay 254. The contacts lock in mechanically. Momentary energization of the winding 254d releases the contacts. In addition to the contacts 254a and 254b already mentioned, the relay 254 is provided with normally open contacts 254e and normally closed contacts 254f. A pushbutton switch 276 is provided to energize the winding 254c of the relay 254. The switch 276 may be operated by the serviceman when he fills the machine. An energizing circuit for the winding 254c may be traced from the power lead 190 through the override switch 160, the delivery switch 158, the normally closed relay contacts 254f, a lead 280, the switch 276, and the winding 254c to the power lead 192. When the vending unit 26 is empty, the switches 160 and 158 are in the illustrated positions and the contacts 254f are closed. Thus, closure of the switch 276 is sufficient to energize the winding 254c and shift the contacts 254a, 254b, 254e, and 254f to their actuated positions. The opening of the normally closed contacts 254f immediately de-energizes the winding 254c, but the relay 254 locks in mechanically, as already indicated.

20 As already indicated, actuation of the relay 254 closes the contacts 254a and 254b, which are located in the energizing circuits for the conveyor relay 248 and the conveyor motor 84. As a result, the conveyor motor 84 is conditioned for operation in response to closure of the conveyor switch 118.

25 Provision is made for stopping the conveyor motor 84 after all of the milk cartons 22 have been discharged from the vending unit 26. As long as any cartons remain in the channel-shaped trays 92, the conveyor motor 84 will be stopped when the cartons engage and operate the bail 110 so as to open the conveyor switch 118. However, when the vending unit 26 is completely empty, the conveyor motor 84 cannot be stopped in this way.

30 In order to stop the conveyor motor 84 when the vending unit is empty, the unit is provided with a thermal time delay relay 284 having an electric heater element 286 adapted to close a normally open thermostatic switch 288, after the heater element 286 has been energized for a predetermined interval. It will be seen that the electrical heater element 286 is connected across the conveyor motor 84 by means of leads 290 and 292. Thus, the heater element 286 is energized whenever the conveyor motor 84 is operating. The thermostatic switch 288 is connected in an energizing circuit for the release winding 254d of the interlock relay 254. Such circuit may be traced from a lead 270 through the lead 290, the thermostatic switch 288, the normally open contacts 254e and the winding 254d to the power lead 192.

35 While milk cartons 22 remain in the vending unit 26, the conveyor motor 84 operates for only a brief interval sufficient to advance a new row of cartons to the delivery position 108. The thermal time delay relay 284 is arranged so that the normal interval of operation of the conveyor motor 84 will not be sufficient to close the thermostatic switch 288. When the vending unit 26 is empty, however, the conveyor motor 84 operates continuously until the thermostatic switch 288 is closed. As already indicated, the relay contacts 254e are closed at all times during normal operation of the machine. Accordingly, closure of the thermostatic switch 288 energizes the release winding 254d and thereby releases all of the contacts 254a, 254b, 254d and 254e to their normal

positions. The opening of the contacts 254b stops the conveyor motor 84, while the opening of the contacts 254a de-energizes the conveyor motor relay 248. The opening of the contacts 254e de-energizes the release winding 254d. The closure of the contacts 254f energizes an empty light 294. It will be seen that the light 294 is connected between the lead 280 and the power lead 192. The energizing circuit for the light 294 may be traced from the power lead 190 through the over ride switch 160, the delivery switch 158, the normally closed relay contacts 204c, the normally closed relay contacts 254f and the light 294 to the power lead 192. The empty light 294 is visible from the outside of the cabinet, as indicated in Fig. 1 and serves as a warning to the prospective purchaser that the vending unit is empty.

When the service man fills the vending unit, he actuates the relay 254 by closing the push button switch 276 so as to energize the winding 254c. This closes the contacts 254a and 254b and thereby energizes the conveyor motor relay 248 and the conveyor motor 84. The contacts 254e are closed so as to condition the release winding 254d for energization. At the same time, the opening of the contacts 254f extinguishes the empty light 294. The service man can stop the conveyor motor 84 at any time simply by opening the stop switch 266.

In some cases, the service man will find the vending unit 26 only partially empty. In that case he will want to fill the unit completely with milk cartons. In many cases, pusher paddle 126 will be in an intermediate position, between its fully retracted and fully advanced positions. In that case, the service man will want to move the pusher paddle to its fully retracted position so that he can completely fill the channel member 92 at the delivery position 108. In the present case, the service man completes the cycle of the pusher paddle by pressing a double pole push button switch 296. It will be seen that the switch 296 comprises normally open contacts 298 and normally closed contacts 300. Operation of the switch 296 closes the contacts 298 and opens the contacts 300. Closure of the contacts 298 energizes a relay 302 having normally open contacts 302a and 302b and normally closed contacts 302c. An energizing circuit for the relay 302 may be traced from the power lead 190 through the lead 250, the contacts 242 and 244 of the conveyor safety switch 184, a lead 304, the switch contacts 298, the relay contacts 302c, a lead 306 and the relay 302 to the power lead 192. Since the pusher paddle 126 is in an intermediate position, the safety switch 184 is not actuated and the movable contact 242 accordingly is engaging the contact 244. Moreover, the relay contacts 302c are closed. Accordingly, closure of the switch contacts 298 is sufficient to energize the relay 302. Of course, the relay contacts 302c immediately open, but a holding circuit is established through the contacts 302b. Such holding circuit may be traced from the power lead 190 through the override switch 160, the delivery switch 158, the normally closed relay contacts 214b, the normally open relay contacts 302b, the lead 306 and the relay 302 to the power lead 192.

The switch contacts 300 and the relay contacts 302a are in an alternative energization circuit for the vending motor 136. Such circuit may be traced from the power lead 190 through the contacts 242 and 244 of the safety switch 164, the lead 304, the relay 302a, the switch contacts 300, a lead 308, the overload switch 236 and the vending motor 136 to the power lead 192. Energization of the relay 302 closes the contacts 302a. As soon as the push button switch 296 is released, the contacts 300 close and thereby energize the vending motor 136. Accordingly, the pusher paddle 126 will be moved forwardly. Any milk cartons in front of the paddle will be pushed successively off the front end of the channel member 92 at the delivery position. The service man will catch the cartons as they are pushed from the channel mem-

ber. If any of the cartons trips the delivery switch 158, the relay 302 will be de-energized and it will be necessary to reset the relay by again operating the push button switch 296.

When the pusher paddle encounters the override switch 296 the relay 302 will be de-energized, but the vending motor 136 will continue to operate due to the actuation of the override switch. Thus, the finger 138 will become disengaged from the pusher paddle 126 and the paddle will be returned by the spring 142. This will open the override switch 160 so as to stop the vending motor 136. The return of the pusher paddle will operate the safety switch 154 so as to shift the movable contact 242 away from the contact 244 and thereby break the circuit through the switch contacts 300. Accordingly, further operation of the switch 296 will have no effect. With the pusher paddle 126 fully returned, the service man can fill the channel member 92 at the delivery position 108.

A brief review of the operation of the machine may be helpful by way of summary. When a purchaser desires a carton of milk, he deposits an appropriate coin in either of the coin slots 32. The corresponding vending unit 26 immediately delivers a carton of milk to the housing 38 behind the access door 34. It is a simple matter for the purchaser to open the door 34 and remove the milk carton 22. The door 34 closes automatically by the action of gravity, due to the tilted position of the hinge pivots 40 for the door.

The operation of the vending unit 26 commences when the coin is deposited. The coin actuates the switch 196 and thereby shifts the movable contact 198 against the contact 202. This energizes the first vending relay 204. After the coin passes the switch 196, the contact 198 returns to the contact 200, but the first vending relay 204 is held in by the holding circuit established by closure of its own holding contacts 204b. Return of the coin switch 196 energizes the second vending relay 214. If the coin hangs up on the switch 196, the second vending relay 214 will not be energized and the vending unit will not function. The coin selecting mechanism 48 may be provided with a release lever 312 to return any coin that hangs up.

Energization of the second vending relay 214 closes the contacts 214a and thereby energizes the vending motor 136. This advances the chain 130, with the result that the finger 138 on the chain advances the pusher paddle 126. Forward movement is imparted to the row of cartons 22 at the delivery position 108 by the pusher paddle 126. The cartons are slid forwardly along the channel member 92 at the delivery position. Because of the provision of an independent channel member for each row of cartons, the forward movement of the cartons at the delivery position does not affect the other cartons.

After a brief interval, the foremost carton in the row at the delivery position is pushed off the channel member 92 into the delivery chute 48 and thence into the delivery housing 38. As the falling carton enters the delivery chute 48, it swings the delivery trip lever 152 downwardly and thereby opens the delivery switch 158. This de-energizes the vending motor 136 and the relays 204 and 214. The vending unit 26 is thereby conditioned for actuation by another coin.

The vending unit 26 may be provided with an electric counter 314 adapted to be energized through the relay contacts 214c. Thus, the counter 314 will indicate the number of times that the relay 214 has been operated. This count will correspond to the number of cartons vended by the unit.

As the pusher paddle 126 approaches the position in which the last carton 22 at the delivery position will be pushed into the delivery chute 48, the paddle operates the override switch 160. As a result, the vending motor 136 continues to operate after the carton opens the delivery switch 158. The continued operation of the mo-

tor 136 disengages the finger 138 from the pusher paddle 126 and permits the spring 142 to return the paddle to its fully retracted position. The return of the paddle opens the override switch and thereby stops the vending motor 136.

After all of the cartons 22 at the delivery position 108 have been vended, the bail 110 swings to the left and thereby closes the conveyor switch 118. Moreover, the return of the pusher paddle closes the conveyor motor safety switch 164. Closure of these two switches energizes the conveyor relay 248 and thereby closes the relay contacts 248a so as to energize the conveyor motor 84. The conveyor chains 74 carry the channel members 92 to the right along the upper chain flights 86. Accordingly, a new row of cartons 22 is advanced to the delivery position 108. The cartons swing the bail 110 to the right and thereby open the conveyor switch 118. This de-energizes the relay 248 and thereby stops the conveyor motor 84. The operation of the bail 110 closes the vending motor safety switch 122 so that the vending motor 136 can be energized by depositing another coin.

If all of the cartons 22 have been discharged from the vending unit 26, the conveyor motor 84 will continue to operate until the thermal time delay relay 284 energizes the relay winding 254d and thereby releases the relay contacts 254a, 254b, 254e and 254f. The opening of the contacts 254a and 254b de-energizes the conveyor relay 248 and the conveyor motor 84. The opening of the contacts 254e de-energizes the winding 254d. At the same time, the closure of the contacts 254f energizes the empty light 294.

The serviceman resets the relay 254 by operating the push button switch 276 and thereby energizing the winding 254c. This starts the conveyor motor 84. To stop the conveyor motor, the serviceman can open the stop switch 266. He can complete the cycle of the pusher paddle 126 by operating the push button switch 298. This will move the paddle to its fully retracted position so that the channel member 92 at the delivery position 108 can be filled completely with cartons.

It will be evident that the vending machine is reasonably simple in construction and low in cost. Nevertheless, it is positive and foolproof in operation and is capable of vending a carton in a very short time. There is virtually no possibility that the machine will malfunction.

The machine may be filled and serviced very conveniently. If any major servicing is necessary, the vending units may be slid out of the cabinet on their rails. A spare vending unit may be inserted in the cabinet, if necessary.

It will be evident that the machine will hold an unusually large number of cartons. Accordingly, the machine will be highly profitable in operation.

Various modifications, alternative constructions and equivalents may be employed without departing from the true spirit and scope of the invention as exemplified in the foregoing description and defined in the following claims.

I claim:

1. In a machine for vending milk cartons or the like, the combination comprising a conveyor having a horizontal drive shaft, a first pair of spaced sprockets on said shaft, a second pair of sprockets spaced horizontally from said first pair, a pair of endless chains strung around said sprockets and having upper and lower horizontal flights therebetween, a plurality of closely spaced parallel channel members pivotally mounted on said chains and extending therebetween, each of said channel members having a bottom wall and a pair of spaced parallel side wall flanges directed outwardly from said chains, a conveyor motor for driving said shaft to advance said chains and thereby carry said channel members along a path above said upper flights of said chains, horizontal guide rails underlying said path for supporting said channel members, each of said channel members along said path being

adapted to receive and support a plurality of cartons in a row, said conveyor being operative to move said channel members in turn to a delivery position adjacent the end of said path, a pusher paddle at said delivery position, means supporting said paddle for reciprocating movement over and parallel to the channel member at the delivery position to push the row of cartons along said channel member and thereby push each carton in turn off one end thereof, a delivery chute under said one end for receiving the cartons and carrying them away by gravity, a third endless chain parallel to the path of said paddle, a finger on said chain and engageable with said paddle for advancing the same, a vending motor for advancing said third chain, a spring biasing said paddle rearwardly for retracting the same, coin operated means for starting said vending motor to advance said paddle and push a carton into said chute, a movable delivery arm extending into said chute and operable by a carton passing therethrough, means operable by said delivery arm for stopping said vending motor, override means for continuing operation of said vending motor to disengage said finger from said paddle after all cartons at the delivery position have been delivered, said spring thereupon returning said paddle, a swingable bail operable in one direction by any carton at said delivery position, a spring for operating said bail in the opposite direction, means operable by concurrent return of said paddle and movement of said bail in said opposite direction for starting said conveyor motor, to bring a channel member loaded with cartons to said delivery position and thereby operate said bail in said one direction, means operable by movement of said bail in said one direction for stopping said conveyor motor, and a time delay relay for stopping said conveyor after a predetermined interval in the event that all of said channel members are empty.

2. In a machine for vending articles, the combination comprising a conveyor having a horizontal drive shaft, a first pair of spaced sprockets on said shaft, a second pair of sprockets spaced horizontally from said first pair, a pair of endless chains strung around said sprockets and having upper and lower horizontal flights therebetween, a plurality of horizontal closely spaced parallel channel members pivotally mounted on said chains and extending therebetween, each of said channel members having a bottom wall and a pair of spaced parallel side wall flanges directed outwardly from said chains, a conveyor motor for driving said shaft to advance said chains and thereby carry said channel members along a path above said upper flights of said chains, horizontal guide rails underlying said path for slidably engaging and supporting said channel members, each of said channel members along said path being adapted to receive and support a plurality of articles in a row, said conveyor being operative to move said channel members in turn to a delivery position adjacent the end of said path, a pusher paddle at said delivery position, means supporting said paddle for reciprocating movement over and parallel to the channel member at the delivery position to push the row of articles along said channel member and thereby push each article in turn off one end thereof, a delivery chute under said one end for receiving the articles and carrying them away by gravity, a third endless chain parallel to the path of said paddle, a finger on said chain and engageable with said paddle for advancing the same, a vending motor for advancing said third chain, yieldable means biasing said paddle rearwardly for retracting the same, coin operated means for starting said vending motor to advance said paddle and push an article into said chute, a movable delivery arm extending into said chute and operable by an article passing therethrough, means operable by said delivery arm for stopping said vending motor, override means for continuing operation of said vending motor to disengage said finger from said paddle after all articles at the delivery position have been delivered, said yieldable means thereupon returning said

paddle, a swingable detector arm operable in one direction by any article in the row at said delivery position, yieldable means for operating said detector arm in the opposite direction, means operable by concurrent return of said paddle and movement of said detector arm in said opposite direction for starting said conveyor motor to bring a channel member loaded with articles to said delivery position and thereby operate said detector arm in said one direction, and means operable by movement of said detector arm in said one direction for stopping said conveyor motor.

3. In a machine for vending milk cartons or other articles, the combination comprising a conveyor having a horizontal drive shaft, a first pair of spaced sprockets on said shaft, a second pair of sprockets spaced horizontally from said first pair, a pair of endless chains strung around said sprockets and having upper and lower horizontal flights therebetween, a plurality of horizontal closely spaced parallel channel members mounted on said chains and extending therebetween, each of said channel members having a bottom wall and a pair of spaced parallel side wall flanges directed outwardly from said chains, a conveyor motor for driving said shaft to advance said chains and thereby carry said channel members along a path above said upper flights of said chains, horizontal guide rails underlying said path for slidably engaging and supporting said channel members, each of said channel members along said path being adapted to receive and support a plurality of articles in a row, said conveyor being operative to move said channel members in turn to a delivery position adjacent the end of said path, a pusher paddle at said delivery position, means supporting said paddle for movement along the channel member at the delivery position for pushing the row of articles along said channel member and thereby sliding each article in turn off one end thereof, a delivery chute under said one end for receiving the articles and carrying them away by gravity, means including a vending motor for advancing said paddle, coin operated means for starting said vending motor to advance said paddle and push an article into said chute, a movable delivery arm extending into said chute and operable by an article passing therethrough, means operable by said delivery arm for stopping said vending motor, a swingable detector arm operable in one direction by any article in the row at said delivery position, yieldable means for operating said detector arm in the opposite direction, means operable by movement of said detector arm in said opposite direction for starting said conveyor motor to bring a channel member loaded with articles to said delivery position and thereby operate said detector arm in said one direction, and means operable by movement of said detector arm in said one direction for stopping said conveyor motor.

4. In a machine for vending articles, the combination comprising a conveyor having a horizontal drive shaft, a first pair of spaced sprockets on said shaft, a second pair of sprockets spaced horizontally from said first pair, a pair of endless chains strung around said sprockets and having upper and lower horizontal flights therebetween, a plurality of horizontal closely spaced parallel channel members pivotally mounted on said chains and extending therebetween, each of said channel members having a bottom wall and a pair of spaced parallel side wall flanges directed outwardly from said chains, a conveyor motor for driving said shaft to advance said chains and thereby carry said channel members along a path above said upper flights of said chains, horizontal guide means underlying said path for slidably engaging and supporting said channel members, each of said channel members along said path being adapted to receive and support a plurality of articles in a row, said conveyor being operative to move said channel members in turn to a delivery position adjacent the end of said path, a pusher at said delivery position, means supporting said pusher for movement along the channel member at the delivery position for pushing the row of articles along said channel member and thereby slide each article in turn off the front end thereof, a delivery chute under said front end for receiving the articles and carrying them away by gravity, means including a vending motor for advancing said pusher, coin operated means for starting said vending motor to advance said pusher and push an article into said chute, a movable delivery arm extending into said chute and operable by an article passing therethrough, means operable by said delivery arm for stopping said vending motor, a swingable detector arm operable in one direction by any article in the row at said delivery position, yieldable biasing means for operating said detector arm in the opposite direction, means operable by movement of said detector arm in said opposite direction for starting said conveyor motor to bring a channel member loaded with articles to said delivery position and thereby operate said detector arm in said one direction, and means operable by movement of said detector arm in said one direction for stopping said conveyor motor.

pusher for movement along the channel member at the delivery position, said pusher being engageable with the rear of the rearmost article in the channel member at the delivery position and being movable forwardly, to push the row of articles along said channel member and thereby slide each article in turn off the front end thereof, means including a vending motor for advancing said pusher, coin operated means for starting said vending motor to advance said pusher and push an article off the front end of the channel member at the delivery position, a movable delivery arm in front of the delivery position and operable by the article pushed from said conveyor, means operable by said delivery arm for stopping said vending motor, a swingable detector arm operable in one direction by any article in the row at said delivery position, yieldable biasing means for operating said detector arm in the opposite direction, means operable by movement of said detector arm in said opposite direction for starting said conveyor motor to bring a channel member loaded with articles to said delivery position and thereby operate said detector arm in said one direction, and means operable by movement of said detector arm in said one direction for stopping said conveyor motor.

5. In a machine for vending articles, the combination comprising a conveyor having a horizontal drive shaft, a first pair of spaced sprockets on said shaft, a second pair of sprockets spaced horizontally from said first pair, a pair of endless chains strung around said sprockets and having upper and lower horizontal flights therebetween, a plurality of horizontal closely spaced parallel channel members pivotally mounted on said chains and extending therebetween, each of said channel members having a bottom wall and a pair of spaced parallel side wall flanges directed outwardly from said chains, a conveyor motor for driving said shaft to advance said chains and thereby carry said channel members along a path above said upper flights of said chains, horizontal guide means underlying said path for slidably engaging and supporting said channel members, each of said channel members along said path being adapted to receive and support a plurality of articles in a row, said conveyor being operative to move said channel members in turn to a delivery position adjacent the end of said path, a pusher at said delivery position, means supporting said pusher for movement along the channel member at the delivery position, said pusher being engageable with the rear of the rearmost article in the channel member at the delivery position and being movable forwardly to push the row of articles along said channel member and thereby slide each article in turn off the front end thereof, a delivery chute under said front end for receiving the articles and carrying them away by gravity, means including a vending motor for advancing said pusher, coin operated means for starting said vending motor to advance said pusher and push an article into said chute, a movable delivery arm extending into said chute and operable by an article passing therethrough, means operable by said delivery arm for stopping said vending motor, a swingable detector arm operable in one direction by any article in the row at said delivery position, yieldable biasing means for operating said detector arm in the opposite direction, means operable by movement of said detector arm in said opposite direction for starting said conveyor motor to bring a channel member loaded with articles to said delivery position and thereby operate said detector arm in said one direction, and means operable by movement of said detector arm in said one direction for stopping said conveyor motor.
